UNITED STATES PATENT OFFICE.

ALBERT E. LYTLE, OF CHICAGO, ILLINOIS, ASSIGNOR OF ONE-HALF TO
NANCY G. BARRETT, OF SAME PLACE.

DESIGN FOR A VAPOR-BURNER.

SPECIFICATION forming part of Design No. 31,713, dated October 24, 1899.

Application filed September 9, 1899. Serial No. 730,032. Term of patent 14 years.

To all whom it may concern:

Be it known that I, ALBERT E. LYTLE, a citizen of the United States, residing at Chicago, in the county of Cook and State of Illinois, have invented and produced a new and original Design for Vapor-Burners, of which the following is a specification, reference being had to the accompanying drawings, forming part thereof.

Figure 1 is a perspective view of a vapor-burner, showing my new design; and Fig. 2 is a bottom plan view thereof.

As shown in the drawings, the leading or material feature of my design consists of a disk or plate A, whose lower surface is concave and is provided at its rim with a series of radial corrugations or indentations a. The upper surface of the plate or disk A is formed with a cylindrical enlargement B, having a boss or enlargement b' on its top.

Located diametrically opposite each other in the wall of the portion B are screw-thread-

ed openings c and c', as is clearly shown in the drawings. Extending from the lower surface of the plate A is a tubular portion C, 25 whose lower part is bent and upturned so as to occupy a position directly below the center of the plate or disk A and has on its free end an enlargement D, provided with an opening d in the center of its top. The lower surface 30 of the plate A is also formed with two lugs or bosses e and e', having internal screw-threads.

Having described my invention, what I claim as new, and desire to secure by Letters Patent, is—

The design for a vapor-burner, as herein shown and described.

In testimony whereof I have signed my name to this specification in the presence of two witnesses.

ALBERT E. LYTLE.
